UNITED STATES PATENT OFFICE.

JAMES CLOSE, OF NEWARK, NEW JERSEY.

ART OF FORMING JOINTURE MEANS UPON TUBULAR MEMBERS.

1,093,914.

Specification of Letters Patent. Patented Apr. 21, 1914.

Application filed August 3, 1912. Serial No. 713,066.

To all whom it may concern:

Be it known that I, JAMES CLOSE, a citizen of the United States, residing in the city of Newark, county of Essex, and State 5 of New Jersey, have invented certain new and useful Improvements in Art of Forming Jointure Means Upon Tubular Members, of which the following is a specification.

10 My invention relates to improved and simplified means for securing screw-threaded members to structures formed of thin sheet metal or tubing, particularly the latter, and has for its object the provision of a simple 15 and efficient joint permitting the use of stock much lighter in weight than it has hitherto been found possible to use for such purposes. For purposes of illustration I have shown a section of tubing such as that 20 used for the frame-work of brass bedsteads and connected thereto the filler rods which are customarily used to form the remainder of the upright frame-work.

In the accompanying drawings which 25 form a part of this specification, Figure 1 is a side elevation of a portion of such frame-work, parts being broken away to show the application of my improvement; Fig. 2 is a transverse sectional view of a 30 section of tubing showing the first operation to which it is subjected in making my improved joint; Fig. 3 is a similar view showing a further stage, and Fig. 4 is an enlarged sectional view of a section of sheet 35 tubing and a rod joined thereto by my novel method.

Referring to the drawings in detail, the 40 numeral 1 designates a section of metal or other tubing to which are secured rods 2 and the balls 3 in the manner hereinafter set forth. Hitherto in the construction of 45 tubular metal work such as brass bedsteads it has been customary to drill a hole radially through the shell of the tube for the reception of rods or other structures which were 50 to be secured thereto. The drilled hole was then tapped with a screw thread, and a correspondingly externally threaded rod or the like screwed into the thread thus formed. 55 While this practice has been universal, it is extremely wasteful for the reason that it requires the use of a sufficient thickness of stock to receive a plurality of threads when the hole is drilled through the stock. The 60 requirements of strength, however, would dictate the use of much thinner stock, and

the necessity for stock of sufficient weight to receive the screw threads has been controlling in the selection of tubing. By reducing this requirement I therefore permit 60 the use of much thinner tubing, which results in an article amply strong and more desirable because of the reduction in weight.

In making my improved joint, I first 65 punch a hole radially through the shell of the tube or similar structure with a blunt instrument, which results in the forcing inward toward the center of the tube of a lip or bur of metal, which finally breaks with a jagged tear.

The numeral 4 designates this lip or bur. 70 A tap is then inserted in the opening thus formed and screw threads 5 cut upon the interior of the lip. It will be obvious that by this method the amount of material 75 which is provided for the reception of the threads is greatly in excess of the normal thickness of the metal, for instead of the waste of metal which normally occurs in drilling a hole in the tube, this metal is 80 conserved and appears as the lip or bur, which is as efficient to receive the threads as the body of the tube itself. The edges of this lip or bur extending within the tube 85 will be jagged, but these outstanding ridges I find in practice to be sufficiently stable to withstand the action of the tap and receive the thread.

While I am aware that my invention is 90 particularly adapted for use with circular tubing composed of a more or less ductile material, it is also useful in connection with a tubular member having straight sheet metal sides, a section of which is illustrated 95 in Fig. 4, wherein the sheet 6 carries the lip 7 or bur formed as above described and threaded at 8 for the reception of the externally threaded rod 9 or the like.

Having thus described my invention, I 100 claim:

1. The method of forming jointure means upon a tubular member composed of thin material which consists in piercing the member from the outside without supporting the adjacent material from the inside, thereby 105 producing a lip or bur on the opening thus formed, the axial length of the wall of said opening thus being substantially greater than the original thickness of the material, and then fashioning locking means upon 110 the inner surface of said wall.

2. The method of forming jointure means

upon a tubular member composed of thin material which consists in piercing the member from the outside without supporting the adjacent material from the inside, thereby 5 producing a lip or bur on the opening so formed, the axial length of the wall of said opening thus being substantially greater

than the original thickness of the material, and then fashioning a screw thread upon said wall.

JAS. CLOSE.
